VASE OR SIMILAR ARTICLE

Roland L. Buhrig, Santa Ana, Calif.

Application October 30, 1948, Serial No. 149,398

Term of patent 7 years

(Cl. D29—28)

To all whom it may concern:

Be it known that I, Roland L. Buhrig, a citizen of the United States and a resident of the city of Santa Ana, in the county of Orange and State of California, have invented a new, original, and ornamental Design for a Vase or Similar Article, of which the following is a specification, reference being had to the accompanying drawing, forming part thereof, in which:

Fig. 2 is an end elevation thereof;

Fig. 3 is a top plan view thereof;

Fig. 4 is a side elevation thereof; and

Fig. 5 is an enlarged fragmentary section, taken along a plane corresponding to line 5—5 of Fig. 1.

I claim:

The ornamental design for a vase or similar article, substantially as shown.

ROLAND L. BUHRIG.
